Primary Examiner — George D Kirschbaum*Assistant Examiner* — Clesce Moore, Jr.(74) *Attorney, Agent, or Firm* — Saidman DesignLaw Group, LLC(57) **CLAIM**

The ornamental design for a tire shear band, as shown and described.

DESCRIPTION

FIG. 1 is a perspective view of a tire shear band showing our new design;

FIG. 2 is a front view thereof;

FIG. 3 is a left side view thereof, the right side being a mirror image thereof; and,

FIG. 4 is a top view thereof, the bottom being a mirror image thereof.

The dashed broken lines illustrate structure or features which form no part of the claimed design.

The dot-dash broken lines illustrate boundaries of the claimed design; the dot-dash lines form no part of the claimed design.

The drawings include surface shading, which represents contour and not surface ornamentation. Elements without shading in FIGS. 1 and 2 are through holes.
